UNITED STATES PATENT OFFICE

BENJAMIN PHILLIPS, OF CINCINNATI, OHIO

OIL-DISPENSING MEASURING DEVICE

Application filed April 16, 1928. Serial No. 270,269.

My invention relates to oil dispensing measures and particularly to improvements in such devices which will facilitate the dispensing of heavy lubricants.

5 In the art there are many types of dispensing measures with thumb operated plungers which release valves at the bottoms of the containers so that, when a service man carries the container to charge the oil reservoir under the hood of an engine, no oil will spill on the fenders of the car. As far as I am aware, however, no one has made a dispensing measuring device in which any means are provided for speeding up the flow 15 of lubricant from the container.

It is the object of my invention to provide a dispensing container which will have a thumb operated member which not only will release the lubricant, but which, by proper manipulation, may be utilized for increasing the flow of the lubricant from the measuring vessel.

The above and other objects to which reference will be made in the ensuing disclosure 25 I accomplish by that certain combination and arrangement of parts of which I have illustrated a preferred modification.

Referring to the drawings:—

The figure is a perspective view of the dispensing container with parts broken away to reveal the internal arrangement of parts.

The measuring device comprises a cylindrical vessel 1 having preferably a rounded bottom 2 within which is disposed the outlet port 3. A piece of flexible hose 4 is secured to the bottom 2 so that the hose will dispense any material discharged through the port 3. The tip of the hose has a nozzle portion 5 which may be retained in elevated position 40 behind a clip 6 attached close to the top wall of the vessel.

A handle 7 is secured to the side wall of the vessel, and above the handle in suitable position to be operated by the thumb when 45 the handle is held with the fingers of the hand, is a rocking treadle 8 which is pivoted to a small bracket 9 which is attached to the cylindrical wall of the vessel. Brackets 10 are secured within the walls of the vessel, and these brackets have vertical openings

11 which provide vertical bearings for a pair of plunger rods 12. The plunger rods are connected together by a rod 13 extending across between the tops of the rods. The plungers and top rod may be formed as an 55 integral inverted U-shaped member, as indicated.

A link 14 connects the inner end of the treadle with the rod 13 and plungers 12. A disc 15, which may, as indicated, have a flanged periphery and which fits fairly snugly 60 within the cylindrical walls of the vessel, is secured to the bottoms of the plunger rods by means of lugs 16. Springs 17 tend to force the disc into seating position at the 65 bottom of the vessel. Within the disc is a port 18 having a strip 19 extending across the port in which is mounted the stem 20 of a disc valve 21.

The drawing shows the device in the position which it assumes when the service man presses down on the end of the treadle, thereby releasing the charge of lubricant for dispensing.

The operation of the device will be apparent. With the treadle released the operator fills the vessel. He then opens up the oil hole to discharge the contents. When he pushes down on the treadle the parts assume the position illustrated in the drawings. The 70 disc is elevated from the bottom of the vessel forming a partial vacuum, and the valve 21 dropping down opens the port 18 and the lubricant flows down through the port 3 into the dispensing tube. If the material flows 75 slowly the operator moves the treadle up and down with his thumb. With the down stroke the valve 21 moves back to close the port 18 and the disc acts as a force pump. The succeeding up stroke of the disc allows another 80 charge to flow down into the compartment between the disc and the bottom wall of the vessel.

While I prefer to construct the dispensing devices in accordance with the preferred arrangement illustrated, such construction will, of course, be subject to mechanical changes which incorporate the same inventive principle.

In use during cold weather with heavy 100

lubricant the time which a service man can save in servicing automobiles with lubricant is very surprising. Instead of sometimes as long as three or four minutes, the charge may be dispensed in a few seconds.

Having thus described my invention, what I claim as new and desire to secure by Letters Patent, is:—

1. A dispensing device comprising a measuring vessel for receiving a charge of liquid to be dispensed, a dispensing conduit arranged in the bottom of the vessel, and means for increasing the flow of material through said conduit comprising a disc fitting loosely within the container and having a check-valved port therein, and means for manually operating said disc as a piston, said means comprising a pair of plunger rods attached to said disc at their lower ends, and an operating handle pivotally connected by means of a link and yoke to said plunger rods at their upper ends, said handle being pivotally mounted on the container wall at a point intermediate its length, and said plunger rods being provided with springs whereby said disc is normally forced into position seating against the bottom of the vessel.

2. A dispensing device comprising a measuring vessel for receiving a charge of liquid to be dispensed, a dispensing conduit arranged in the bottom of the vessel, and means for increasing the flow of material through said conduit comprising a disc fitting loosely within the container and having a check-valved port therein, and means for manually operating said disc as a piston, said means comprising push rods and a pivoted treadle having an actuating end portion accessible to the thumb when the vessel is held within the hand, said push rods connected at their lower ends to said disc, and said pivoted treadle having a link and yoke connection with said push rods at their upper ends.

3. A dispensing measure having a bottom discharge conduit, and being provided with a normally closed valve for preventing the flow of liquid through said discharge conduit, manually operated means for opening said valve, said means providing means for speeding up the flow of liquid through said conduit.

4. A dispensing measure having a bottom discharge conduit, and being provided with a normally closed valve for preventing the flow of liquid through said discharge conduit, manually operated means for opening said valve, said means providing means for speeding up the flow of liquid through said conduit, and comprising a disc retained within the bottom portion of said measure, said disc having a port with a check valve mounted therein and means for reciprocating said disc, comprising a pivoted treadle, plunger rods connected with said treadle and

said plunger rods resiliently connected with said disc.

5. A dispensing measure having a bottom discharge conduit, and being provided with a normally closed valve for preventing the flow of liquid through said discharge conduit, manually operated means for opening said valve, said means providing means for speeding up the flow of liquid through said conduit, and comprising a disc slidably retained within the bottom portion of said measure, said disc having a port with a check valve mounted therein and said disc having a pair of plunger rods resiliently attached thereto and a treadle member for actuating said plunger rods, connected with said treadle member.
